UNITED STATES PATENT OFFICE.

JAMES G. BLUNT, OF SCHENECTADY, NEW YORK.

LOCOMOTIVE-CAB TURRET.

Application filed September 23, 1926. Serial No. 137,225.

My invention relates to an improved construction of locomotive cab and turret, and contemplates forming the front wall of the cab with a detachable center section, having 5 an opening for the passage of the various pipes, valves, and valve stems, leading to the turret, the turret serving as closure for the opening.

It has been the practice, heretofore, to permanently secure the front wall of sheet metal cabs, to the side walls and roof, by rivets, and to form a number of holes through the central portion on the front wall, for the passage of the various pipes, valves, and 15 valve stems leading to the turret, which is disposed on the top of the boiler, away from the front wall. This practice is seriously objectionable, in that the holes soon become enlarged to an extent permitting undesirable 20 currents of air to enter the cab. A further objection is that all of the connections leading to the turret must be disconnected therefrom, whenever the cab is removed for repairs, and re-connected when the cab is again 25 installed. This latter difficulty involves a material loss in time and labor.

An object of the present invention, accordingly, is to provide an improved construction of front wall and turret, whereby 30 the various disadvantages noted in connection with cab front wall and turret construction, heretofore known, are completely eliminated.

The improvement claimed is hereinafter 35 fully set forth.

In the accompanying drawings: Figure 1 is a side view, in elevation, of the upper part of the rear end of a locomotive, with a portion of the front of the cab broken away, 40 to show the connection between the front wall and turret; Fig. 2, a plan view, in section, on an enlarged scale, through the central portion of the front wall of the cab, showing its connection to the boiler and turret; Fig. 3, a transverse section through the upper part of the cab, showing the manner 45 of attachment of the front wall, to the boiler and turret; and, Fig. 4, an enlarged section of the front wall of the cab and the upper 50 rear end of the boiler, showing the details of the detachable connection between the front wall and the turret.

In the practice of my invention, referring 55 descriptively to the specific embodiment thereof which is herein exemplified, the construction comprises a boiler, A, to which is

attached the cab, B, having a roof, 10, side walls, 11, and a front wall, C, all made of sheet metal. The front wall comprises two side sections, 12, each being of a width to 60 accommodate the windows, 12^a, and a centre section, 12^b, which is substantially arch shape, and is detachably secured at each of its opposite ends, to one of the side sections, by the welt strips, 12^c. Each welt strip is 65 permanently secured to the side section by rivets, 12^d, and detachably secured to the centre section by bolts, 12^e.

To permit passage through the front wall of the various valve bodies, 13, and stems, 14, leading to the turret, there is provided centrally of the centre section, an elongated opening, 13^f. In order to provide for closing the opening, 13^f, the turret, D, is formed with an elongated manifold, having a rear wall, 15, which completely closes the opening, and is extended to provide a flange, 15^b, having bolt holes, that receive the bolts, 15^c, which pass through suitable holes in the front wall, securing the centre section and 75 turret together.

The rear wall, 15, of the manifold, is provided with openings, into some of which are tapped the valve bodies, 13, and through some of which pass the valve stems, 14. 80 The front wall, 15^a, of the manifold, is provided with openings, into which are fitted the valve seats, 16. The valve seat openings are disposed in axial alignment with the valve stem openings in the rear wall, 15, of 85 the manifold.

For the purpose of giving a strong support to the valve stems, there is provided a bracket, comprising a cross piece, 17, having suitable openings for the valve stems, and 90 a vertical member, 18, at each end of the cross piece, bolted thereto and to the back head of the boiler.

From the foregoing description, it will be 95 obvious that when it is desired to remove the cab from the locomotive, the centre section, 12^b, may be disconnected from the side sections, by removing the bolts, 12^e. The cab, with the side sections of the front wall, may then be lifted off the locomotive, as a unit. 100 The improved construction eliminates the necessity present in constructions heretofore known, of disconnecting the various connections and valves leading into the cab from the turret prior to removing the cab for repairs, and reconnecting them, when the cab is 105 again installed. A further advantage of the 110

improved construction, is that it eliminates the holes heretofore made in the front wall, for the various connections, which holes soon become enlarged in service, permitting undesirable air currents to enter the cab.

I claim as my invention and desire to secure by Letters Patent:

1. A cab turret for locomotives, having a wall formed with a plurality of openings 10 for tapping of connections, said wall being adapted to form a closure for an opening in the front wall of a cab, through which the connections pass.
2. In a cab turret for locomotives, the combination of a wall formed with a plurality of openings for tapping of connections, said wall being adapted to form a closure for an opening in the front wall of a cab, through which the connections pass; 20 and means for attaching the turret to the cab wall in position to close said opening.
3. In a cab turret, the combination of a wall formed with a plurality of openings for tapping of connections, and adapted to 25 form a closure for an opening in the front wall of a cab, through which the connections pass; and a flange, for attaching the turret to the cab wall, in position to close said opening.
4. In a locomotive, the combination of a cab having a front wall formed with an opening for the passage of connections to the turret; and a turret having a face closing said opening.
5. In a locomotive, the combination of a cab, having a front wall formed with an opening; and a turret, closing said opening.
6. In a locomotive, the combination of a cab, having a front wall, formed with an 40 opening; and a turret, attached to said front wall, and closing said opening.
7. In a locomotive, the combination of a cab, having a front wall, formed with an opening; a turret, having a face adapted to close said opening; a flange, for securing the turret to the wall with the face closing said opening; and means for securing the flange to the wall.
8. In a locomotive, the combination of a cab, having a sheet metal front wall embodying a detachable section, said section having an opening therethrough; and a turret closing said opening.
9. In a locomotive, the combination of a cab, having a sheet metal front wall, embodying a detachable section, said section having an opening therethrough, for the passage of connections to the turret; a turret, having a wall closing said opening; a flange for securing the turret to the section; and means for securing the flange to the section.
10. In a locomotive, the combination of a cab, having a sheet metal front wall, em-

bodying side sections, and a centre section, 65 detachably connected to said side sections, said centre section having an opening; and a turret, having a face closing said opening.

11. In a locomotive, the combination of a cab, having a sheet metal front wall, embodying side sections, a centre section, and means for detachably connecting the centre section to the side sections, said centre section having an opening for the passage of connections to the turret; a turret, having a wall closing said opening; and means securing the turret to the centre section.

12. In a locomotive, the combination of a cab, having a sheet metal front wall, embodying side sections, a centre section, and bolts for detachably connecting the centre section to the side sections, said centre section having an opening therethrough, for the passage of connections to the turret; a turret having a face formed with openings for the tapping of connections, said wall closing the opening in the centre section; a flange, extending beyond said face, and formed with bolt holes; and bolts, passing through the holes in the flange and through the centre section to secure the centre section to the turret.

13. In a locomotive, the combination of a cab, having a front wall, embodying two side sections, and a sheet metal centre section; a welt strip, overlying each of the joints between the centre section and the side sections, each welt strip being detachably connected to one of the sections, the said centre section having an opening for the passage of connections to the turret; a turret, having a face closing said opening; and means for securing the turret to the centre section.

14. In a locomotive, the combination of a cab, having a front wall, embodying two side sections detachably secured to a sheet metal centre section, said centre section having an opening for the passage of valves and valve stems; a turret, embodying an elongated manifold having a face formed with openings for the passage of valve stems, and openings to which valve bodies are tapped, the said face closing the opening in the centre section; and means for securing the centre section to the manifold.

15. In a locomotive, the combination of a boiler; a cab, having a front wall formed with an opening for the passage of valves and valve stems; a cab turret, connected to the boiler, and embodying a manifold having a face closing the opening in the front wall; valve stems, extending forwardly from said face through the opening in said wall; and a bracket for supporting the valve stems in position.
